UNITED STATES PATENT OFFICE

123,501

DESIGN FOR A PASSENGER BOAT

William E. Hogreff, Chicago, Ill.

Application January 19, 1939, Serial No. 82,437

Term of patent 14 years

To all whom it may concern:

Be it known that I, William E. Hogreff, a citizen of the United States, residing at Chicago, in the county of Cook and State of Illinois, have invented a new, original, and ornamental Design for Passenger Boat, of which the following is a specification, reference being had to the accompanying drawing, forming part thereof.

I claim:

The ornamental design for a passenger boat, as shown.

WILLIAM E. HOGREFF.
